CLAIM

The ornamental design for a display screen or portion thereof
with animated graphical user interface, as shown and
described.

DESCRIPTION

FIG. 1 is a front view of a display screen or portion thereof
with animated graphical user interface showing a first image
of our new design;

FIG. 2 is a second image thereof;

FIG. 3 is a third image thereof;

FIG. 4 is a fourth image thereof;

FIG. 5 is a fifth image thereof; and,

FIG. 6 is a sixth image thereof.

The outermost broken lines in the figures show a display
screen or portion thereof, and form no part of the claimed
design. The other broken lines in the figures show portions of
the animated graphical user interface, that form no part of the
claimed design.

The appearance of the animated images sequentially transitions
between the images shown in FIGS. 1-6. The process or
period in which one image transitions to another forms no part
of the claimed design.
